UNITED STATES PATENT OFFICE.

FRED. R. SEIDENSTICKER, OF WEST MERIDEN, CONNECTICUT, ASSIGNOR TO
BRADLEY & HUBBARD MANUFACTURING COMPANY, OF SAME PLACE.

DESIGN FOR LAMP-BRACKET.

SPECIFICATION forming part of Design No. 11,823, dated June 15, 1880.

Application filed May 10, 1880. Term of patent 7 years.

To all whom it may concern:

Be it known that I, FRED. R. SEIDENSTICKER, of West Meriden, in the county of New Haven and State of Connecticut, have 5 invented a new Design for Lamp-Brackets; and I do hereby declare the following, when taken in connection with the accompanying drawing and the letters of reference marked thereon, to be a full, clear, and exact description of the 10 same, and which said drawing constitutes part of this specification, and represents a side view.

This invention relates to a design for lamp-brackets, such as made for attachment to the wall, or may be as one of the branches to a 15 chandelier; and the invention consists in the configuration and ornamentation, as shown in the accompanying illustration.

The main arm of the bracket starts from a square boss, *a*, which is substantially the point 20 of attachment, and, running downward, curves outward to the key *b*. The surface of the arm has a plain border at the edge. This border on the lower edge divides, one branch turned upward in scroll form and the other downward.

25 Beyond the key the arm turns upward to the lamp-seat *c*. This arm has a similar bor-

der on each edge, which is wrought into scroll-work near the key, corresponding to that on the opposite side.

Above the boss *a* the arm extends upward 30 then, curving outward, turns at right angles, and thence downward, connecting with the scroll-work of the arm below.

The key *b* is in form of a star, and above it is a representation of scroll-work, forming a 35 central ornament in the bracket, all as shown in the accompanying illustration.

I claim—

The design for lamp-bracket, consisting of the principal arm, starting from the boss *a* 40 downward and curved outward to the key, thence upward to the lamp-seat, ornamented by scroll-work, and above the boss extending upward, turned outward, thence down, and connecting with the scroll-work of the arm below, 45 all as described, and shown in the accompanying illustration.

FRED. R. SEIDENSTICKER.
